United States Patent Office

Des. 203,186

Patented Dec. 14, 1965

203,186

SPEAKER FOR TELEPHONE SYSTEMS

George Bruce Kamp, Springfield, Pa., assignor, by mesne assignments, to ITT Terryphone Corporation, Harrisburg, Pa., a corporation of Delaware

Filed July 9, 1964, Ser. No. 80,779

Term of patent 14 years

(Cl. D26—14)

FIG. 2.

FIG. 3

FIG. 1.

FIG. 1 is a front elevational view of a speaker for telephone systems embodying the invention as seen along the line of sight slightly below an imaginary horizontal plane.

FIG. 2 is a perspective view of a speaker for telephone systems embodying the invention, and

FIG. 3 is a vertical cross-sectional view of a speaker for telephone systems embodying the invention.

The dominant features of my new design are shown in solid lines in the drawing.

I claim:

The ornamental design for a speaker for telephone systems, substantially as shown and described.
